DOUBLE-PANELED LOUVER JALOUSIE STRUCTURE

Joseph E. Pilson, El Portal, Fla.

Application December 9, 1955, Serial No. 552,159

7 Claims. (Cl. 20—62)

This invention relates to pivotable louvered window construction and, more particularly, to jalousie structures in which the louvers each embody plural panes or panels arranged in a common louver frame in parallel and spaced-apart relation.

An object of the invention is to provide a jalousie window structure wherein the louvers are pivotable to an open position effective to pass air but inhibiting the entry of rain therethrough.

Another object is to provide a double-paneled jalousie window which will be efficient in use and simple and compact in assembly.

A further object is to provide a pivotable-louvered window structure which may be readily and economically fabricated.

Yet another object of the invention is to provide a double-paneled jalousie window having, when the louvers therein are closed, an air space intermediate the inner and outer panels whereby to promote thermal insulating characteristics residing in the window structure.

These and other advantages of the invention will be discernible from the detailed description thereof hereinafter set forth.

According to the invention, the window structure comprises a frame in which is arranged a plurality of superposed louvers having oscillatory movement on horizontal axes between open and closed positions. Each louver has a pair of parallel panels supported at the ends thereof in individual end brackets common to each pair, and the panels of each pair are spaced apart to provide an air space or passage therebetween. The louvers are so constructed and arranged, relative to the frame and to each other, that they are pivotable to an open position wherein the inner panel of one louver is inclined in substantially a common plane with the outer panel of the louver therebelow and in contiguous alignment therewith, the abutting panels forming a baffle adapted to exclude rain but permitting the passage of air therethrough.

Interposed between abutting marginal edges of those panels constituting this baffle, are resilient strips effective to provide weathering closures therebetween and at the same time impart a yieldable characteristic to the edges of the panels whereby to insure the operational clearance between adjacent louvers in passage through their respective paths of rotation.

The invention is embodied in a jalousie structure exemplified in the accompanying drawings in which the views are as follows, like reference characters designating identical or analogous parts throughout the several views:

Fig. 1, a sectional elevation through the window taken in line 1—1, of Fig. 10;

Fig. 2, an enlarged section through line 2—2, Fig. 4;

Fig. 3, an enlarged detail of the resilient strip assembly;

Fig. 4, a section on line 4—4, Fig. 10;

Fig. 5, a fragmentary enlarged section on line 5—5, Fig. 4, of the bottom flap structure;

Fig. 6, a sectional elevation on line 6—6, Fig. 1;

Fig. 7, a section on line 7—7, Fig. 5;

2

Fig. 8, a section on line 8—8, Fig. 2;

Fig. 9, a fragmentary transverse sectional elevation through a modified form of the invention, taken on line 9—9, Fig. 11;

Fig. 10, a front elevation in part of the window; and Fig. 11, a fractional front elevation of the window shown in section in Fig. 9.

Referring now to Figs. 1 and 4, the jalousie structure has a frame comprising a head 1, a pair of opposed jambs 2 and 3, and a sill member stepped at two levels 4 and 4' and including an upstanding intermediate dwarf wall 5 extending from jamb to jamb for a purpose to be presently set forth. The frame includes the usual marginal trim members, there being a sill front trim 6 and rear trim 7, jamb front trims 8 and rear trims 9. The head includes a downwardly directed front trim member 10.

Arranged between the jambs, is a plurality of louvers each comprising an inner panel 11 and in parallel relation thereto an outer panel 12 spaced therefrom to provide an air space or passage therebetween.

The inner panels 11 (Fig. 2), have a top rail 13 generally defining a downturned channel, and a bottom rail 14 generally describing an H-shape in cross-section. Between the opposed upper and lower grooves thus formed, a glass pane P which forms the body of the inner panel 11 is received. The outer panels 12 have a top rail 15 generally defining an H-shape in cross-section and a bottom rail 16 in the form of an upturned channel in cross-section. Between opposed grooves thus formed is received a glass pane P' defining the body portion of the outer panels 12. A modification from the foregoing rail patterns resides in the topmost louver wherein the top rail 17 in the outer panel and, in the lowermost louver the bottom rail 18 in the inner panel, respectively assume downturned and upturned channel forms as clearly shown in Fig. 1.

Arranged at the ends of each louver for the common support of the inner and outer panels embodied therein (Figs. 2 and 8), is an end bracket having an end wall 19 against the inner face of which are formed an inner pair 20 and outer pair 21 of inwardly projecting flanges respectively adapted to receive the side marginal edges of the panes P and P'.

Flanges 20 and 21 constitute corresponding side rails which may be separably united in any manner conventional in the art with the top and bottom rails hereinabove described whereby to form the marginal frames within which the panes P and P' may be removably supported.

End walls 19 are pivotably connected by pivot pins 22 to adjacent jamb structure in relation to the faces of which the end walls have slideable movement in a working fit thereagainst. These pins are preferably but not necessarily aligned to define a central axis through the louvers whereby to promote dynamic balance throughout the respective paths of rotation thereof.

The louvers are actuated in oscillatory movement by suitable operator mechanisms conventional in the art such, for example, as shown in Figs. 1, 4, and 6. These assemblies may include a pair of operator bars 23 arranged at each side of the frame and reciprocable in a vertical path to which each bar is confined by a pair of outwardly flaring marginal flanges 24 extending along the outer face of the bar and adapted to travel in complementary upright slots 25 provided in the adjacent jamb structure. Introduction of bars 23 into the slots 25 may be effected, where the frame assembly does not otherwise permit, through convenient apertures provided in either the head or sill members of the frame.

Fashioned against the rear exposed edge of each bar 23 and along the lowermost portion thereof, is a toothed

rack 26 in mesh with a pinion 27 fixed upon a stub shaft 28 and rotatable thereby to impart reciprocal movement to the bar 23. The stub shaft, journaled as at 29 in a suitable bearing formed in adjacent jamb structure, is rotatable by a driven pulley 30 fixed thereon and connected through a belt cable 31 with a drive pulley 32 mounted (Fig. 6) upon a main shaft 33 therebelow for rotation thereby. If desired, pulleys 30 and 32 may be replaced by corresponding sprocket wheels driveably connected by a chain substituted for the cable 31, as will be understood by those skilled in the art.

The main shaft 33, extending laterally across the frame, is journaled at the ends thereof in a pair of bearings 34 detachably fastened to jamb faces adjacent thereto. Mounted upon shaft 33 is the usual worm wheel 35 driven by a worm 36 carried by a worm shaft 37, journaled at one end in a bearing (not shown) bushed in the trim member 7 through which the shaft projects to receive thereon a crank 38. At the opposite end thereof, the shaft 37 is journaled in a bearing 39 fastened to the adjacent face of the intermediate wall 5. A suitable housing 40, carried by the trim member 7 against the inner face thereof, may enclose the worm wheel assembly and provide support therefor in a manner well known in the art.

The louvers are each operably connected to bars 23 by a link 41 pivoted at one end to the bar and at the opposite end to a bracket 42 fastened against the inner face of adjacent rail structure forming the upper margin of the inner panels 11 whereby reciprocal movement of the bars 23 is seen to oscillate the louvers on the pivot pins 22.

Upon turning the crank 38, oscillatory movement is imparted to the louvers and the panels incorporated therein through intervening operating mechanisms hereinabove described.

Again referring to Fig. 1, the inner and outer panels in their respective planes are staggered relative to each other according to a stagger interval which disposes the outer panels each at a predetermined lower elevation relative to the inner panel corresponding thereto. The spacing adopted between the inner and outer panels, the height of the panels, and the stagger interval thereof may be dimensioned so as to provide a construction and arrangement of louvers which, when pivoted to an open position inclining the louvers at a given angle, bring the bottom edges of the inner panels into substantial engagement with the top edges of the outer panels in the louvers respectively next therebelow.

The louvers thus are pivotable to an open position shown in phantom in which the inner panels 11, except that in the lowermost louver, are inclined in substantially a common plane with the outer panels 12 of the louvers next therebelow and in contiguous relation thereto. The abutting panels will be seen to constitute a baffle fronting the window opening and functioning to exclude rain therefrom. At the same time, the passages designated A intermediate the inner and outer panels function to circulate air between the louvers.

Thus, interior spaces having communication with atmosphere through a jalousie structure to which the principle of the invention is applied may receive ventilation while rain is excluded therefrom.

Referring now to Figs. 2 and 3, the panels constituting the baffle herein described, now styled the baffle panels, include substantially arcuate weatherstrips 43 interposed therebetween. These strips, fabricated from any spring-like material possessing suitable characteristics of tension and resiliency, may be preformed to approximate a U-shape cross-section therethrough. One leg or flange F is fastened as by spot welding or threadable fastenings to the inner face of the H-shaped abutting rails in the baffle panels, as at 15', Fig. 3. The opposite flange F' forms a re-entrant member insertable into the outermost grooves G and free to slideably en-

gage the adjacent inner face of the flange 15" against which this flange is urged by tension residing in the strip 43. The width of the strip may be pre-determined relative to the depth of the grooves G, whereby the loops L intervening between flanges F and F' are yieldably engageable with corresponding loops opposed thereto when the baffle panels are inclined to form the baffle hereinbefore described.

Thus, by virtue of the resilient weatherstrips 43, the louvers in their closed positions and the baffle panels in their inclined positions are provided between abutting elements with a weathertight jointure. The resilient characteristic residing in these weatherstrips insures operative clearances between adjacent louvers in their respective paths of rotation. The end walls 19 may have rounded off portions as at 44 and 45 to assist as may be necessary in effecting the foregoing operative clearances.

When the louvers occupy an upright closed position, the passages therein form a continuous air space to promote thermal insulating properties therein. The head member 1 has a triangular flange 1' formed on the underside thereof to provide an impact face in complementary abutting relation to the top rail of the inner panel 11 therebelow. Further supplemental closures for the window when in closed position may include a similar flange

46 adapted to abut the contiguous bottom rail of the outer panel thereabove, in the lowermost louver. The intermediate wall 5 is engageable along the front face thereof by the bottom rail 18 in this louver, which may be fitted with a hingeable flap 47, Figs. 5 and 7, adapted to close the air passage therethrough. This flap is pivoted to the bottom rail through a hinge barrel 48 having an axial shaft 49 therethrough and extending along the rail 18. When the louvers pivot to open positions, the flap 47 is adapted to drop open for the passage of air therethrough. The usual overlapping lip 50 may be arranged against the exterior surfaces of the outer panel bottom rails to provide weathering expedients along these jointures.

40 While the invention herein exemplified discloses louver pivoting axes extending centrally thereof, these axes may be arranged along other points of the end walls 19 with corresponding variations in the geometrical relation of the louvers to essential elements of the frame structure. Fig. 9 depicts, for example, a modification employing the so-called "sliding and swinging" movement of the louvers between open and closed positions. In this form, the inner panels 11 carry a bracket 51 which is pivoted at 52 to the operator bar 23. This bracket has a link 53

50 pivoted thereto at 54, the opposite end of the link having a pivotable connection 55 fixed to the jamb structure 3. Upon downward movement of the bar 23, the louvers slide downwardly and rock, simultaneously, to open position shown in phantom. In this construction, the topmost louver would be obstructed by the head trim member 56. This member may then have pivotable connection with the head 1, through a hinge 57 having an axial shaft 58 extending therethrough and along the front marginal edge of the head member 1, as shown in Fig. 11. The

55 trim member may be urged against the outer face of the panel 12 by suitable spring members 59 connected at one end thereof to the underside of the head and at the opposite end to the inner face of the member 56.

Thus, the frame has a spring-biased head trim member 65 which is pivotably connected to the head and swingable outwardly against the bias to accommodate the topmost louver in its movement to open positions, thereby preserving a rain tight closure therebetween.

The invention will be seen to provide double-paneled louver jalousie construction having unique operating and functional characteristics meeting, essentially, the objectives hereinbefore set forth.

It will be understood that the panels making up the louvers may be fabricated or assembled from other than 75 glass or translucent materials, and the invention is, of

course, susceptible of various modifications and changes in design and arrangement without, necessarily, departing from the scope of the appended claims.

Having thus described the invention and the mode of its practice being apparent therefrom, what I claim as new and desire to secure by Letters Patent, is:

1. In jalousie construction including a frame having a pair of opposed jambs and head and sill members therefor, the combination therewith of a plurality of louvers arranged between said jambs and oscillable between open and closed positions, each of said louvers comprising an inner panel and an outer panel disposed in parallel and spaced apart relation to provide a free air passage therebetween, said louvers being pivotable to an open position inclining said inner panels in substantially a common plane with the outer panel of the louver next therewith and in contiguous alignment therewith, the contiguous panels forming a baffle for the exclusion of rain and the passages conducting air through said louvers, said head having a downturned trim member pivotably connected thereto along the frontal marginal edge thereof and in closure engagement with the front face of the topmost of said louvers, the trim member having outward pivotal movement against said topmost louver, spring means urging said trim member into engagement with said topmost louver.

2. In jalousie construction including a frame having a pair of opposed jambs and head and sill members therefor, the combination therewith of a plurality of louvers arranged between said jambs and oscillable between open and closed positions, each of said louvers comprising an inner panel and an outer panel disposed in parallel and spaced apart relation to provide a free air passage therebetween, said louvers having pivotal movement to an open position inclining said inner panels into contiguous engagement with the outer panels of the louver next therewith whereby the contiguous panels form a baffle for the exclusion of rain, said passages functioning as air conduits through said louvers, said head member having a downturned frontal trim member pivotably connected thereto, spring means urging said trim member into closure engagement with the topmost louver, resilient strips interposed intermediate the panels forming said baffle, a hingeable flap closeable against the bottom of the air passage in the lowermost louver when said louvers are in closed position and openable when the louvers pivot to an open position.

3. In jalousie construction including a frame having a pair of opposed jambs and head and sill members therefor, the combination therewith of a plurality of louvers arranged between said jambs and oscillable between open and closed positions, each of said louvers comprising an inner panel and an outer panel in parallel and spaced apart relation to provide a free air passage therebetween, brackets supporting said louvers at opposite ends thereof and pivotally connected through horizontal axes to the jambs adjacent thereto whereby when the louvers pivot to an open position the bottom edge of the inner panel in each louver engages the top edge of the outer panel in the louver next therewith to thereby form a baffle for the exclusion of rain, said passages defining conduits for the circulation of air moving between the exterior and interior sides of said frame, means operable to oscillate said louvers, resilient weatherstrip means interposed between abutting edges of said panels, a downturned trim member pivotally connected to said head along the frontal marginal edge thereof, and biasing means urging said trim member into closure engagement with the topmost louver.

4. In jalousie construction including a frame having a pair of opposed jambs and head and sill members therefor, the combination therewith of a plurality of louvers arranged between said jambs and oscillable between open and closed positions, each of said louvers comprising an inner panel and an outer panel in parallel and spaced

apart relation to provide a free air passage therebetween, brackets supporting said louvers at opposite ends thereof and pivotally connected through horizontal axes to the jambs adjacent thereto whereby when the louvers pivot to an open position the bottom edge of the inner panel in each louver engages the top edge of the outer panel in the louver next therewith to thereby form a baffle for the exclusion of rain, said passages defining conduits for the circulation of air moving between the exterior and interior sides of said frame, means operable to oscillate said louvers, resilient weather stripping means interposed between abutting edges of said panels, and a flap pivotally mounted at one end to said inner panel adjacent said sill and its other end extending in the direction of said outer panel and resting on said sill whereby upon the opening of said louvers, said flap forms a baffle for the exclusion of rain from entering on said sill.

5. In a jalousie construction including a frame having a pair of opposed jambs and head and sill members therefor, the combination comprising a plurality of louvers extending between said jambs and oscillable between open and closed positions, each of said louvers comprising an inner and an outer panel of substantially equal height disposed in parallel and spaced apart relation, first resilient weather stripping means mounted on a lower edge of each of said inner panels in closed position being in contact relation with an upper edge of the next adjacent lower inner panel, second resilient weather stripping means mounted on an upper edge of each of said outer panels in closed position being in contact relation with a lower edge of the next adjacent upper outer panel, said second resilient weather stripping means being disposed in a horizontal plane below that of said first resilient weather stripping means of the next adjacent upper louver, a louver supporting bracket engaging side edge portions of each pair of inner and outer panels, a pivot pin pivotally mounting each of said brackets on said jambs, the distance between adjacent pivot pins being not greater than the distance between the pivot and the first resilient weather stripping means of one louver plus the distance between the pivot pin and the second weather stripping means of the next adjacent lower louver and operating means for simultaneously swinging said louvers to an open position and said first and second resilient weather stripping means of adjacent pairs of panels contacting each other for the exclusion of rain with their respective panels in alignment with each other to form a passage for the circulation of air therethrough.

6. In a jalousie construction including a frame having a pair of opposed jambs and head and sill members therefor, the combination comprising a plurality of louvers extending between said jambs and oscillable between open and closed positions, each of said louvers comprising an inner and an outer panel of substantially equal height disposed in parallel and spaced apart relation, resilient weather stripping means mounted on a lower edge of each of said inner panels in closed position being in contact relation with an upper edge of the next adjacent lower inner panel, said upper edges of each of said outer panels being disposed in a horizontal plane below that of said resilient weather stripping means of the next adjacent upper louver, a louver supporting bracket engaging side edge portions of each pair of inner and outer panels, a pivot pin pivotally mounting each of said brackets on said jambs, the distance between adjacent pivot pins being not greater than the distance between the pivot pin and the resilient weather stripping means of one louver plus the distance between the pivot pin and the upper edge of the outer panel of the next adjacent lower louver, and operating means for simultaneously swinging said louvers to an open position and said resilient weather stripping means engaging said upper edges of said adjacent outer panels when said panels are in alignment to thereby exclude rain and form a passage for the circulation of air through said louvers.

7. In a jalousie construction including a frame having a pair of opposed jambs and head and sill members therefor, the combination comprising a plurality of louvers extending between said jambs and oscillable between open and closed positions, each of said louvers comprising an inner and an outer panel of substantially equal height disposed in parallel and spaced apart relation, resilient weather stripping means mounted on an upper edge of each of said outer panels in closed position being in contact relation with a lower edge of the next adjacent upper outer panel, said resilient weather stripping means being disposed in a horizontal plane below that of a lower edge of each of the next adjacent upper inner panel, louver supporting bracket engaging side edge portions of each pair of inner and outer panels, a pivot pin pivotally mounting each of said brackets on said jambs, the dis-

5 tance between adjacent pivot pins being not greater than the distance between the pivot pin and the lower edge of the inner panel plus the distance between the pivot pin and the resilient weather stripping means of the next adjacent lower louver, and operating means for simultaneously swinging said louvers to an open position and said resilient weather stripping means engaging said lower edges of said adjacent inner panels when said panels are in alignment to thereby exclude rain and form a passage for the circulation of air through said louvers.
